F. A. FELDKAMP,
DUPLEX FUSE CARTRIDGE,
APPLICATION FILED MAY 12, 1920.

1,397,804.

Patented Nov. 22, 1921.

UNITED STATES PATENT OFFICE.

FREDERICK A. FELDKAMP, OF NEWARK, NEW JERSEY.

DUPLEX-FUSE CARTRIDGE.

1,397,804.

Specification of Letters Patent.

Patented Nov. 22, 1921.

Application filed May 12, 1920. Serial No. 380,768.

To all whom it may concern:

Be it known that I, FREDERICK A. FELDKAMP, a citizen of the United States, residing at Newark, in the county of Essex and 5 State of New Jersey, have invented certain new and useful Improvements in Duplex-Fuse Cartridges; and I do hereby declare the following to be a full, clear, and exact 10 description of the invention, such as will enable others skilled in the art to which it appertains to make and use the same, reference being had to the accompanying drawings, and to characters of reference marked 15 thereon, which form a part of this specification.

The present invention relates, generally, to improvements in fuse cartridges; and the invention has reference, more particularly, to an improved construction of multiplex 20 fuse cartridges.

The present invention has for its principal object to provide a safe, cheap, simply constructed and easily operated multiplex fuse cartridge, having the general exterior 25 construction and appearance of a single fuse cartridge, so that the same may be inserted in the usual manner between the cartridge receiving clips connected in the electric circuit to be served, but which is so 30 constructed that its fuses are connected permanently in series from cap to cap, one or more of said fuses being rendered inoperative by manipulatable short circuiting devices, which, after the fuse in service blows, 35 may be moved to provide a bridging electrical connection across the gap left thereby while at the same time putting in service another fuse.

Other objects of the present invention, not 40 at this time more particularly enumerated, will be clearly understood from the following detailed description of the same.

With the various objects of the present invention in view, the same consists, primarily, in the novel construction of multiplex fuse cartridges hereinafter set forth; and the invention consists, furthermore, in the novel arrangements and combinations of the various parts, as well as in the details of 50 the construction thereof, all of which will be hereinafter more fully described and claimed.

The invention is clearly illustrated in the accompanying drawings, in which:—

55 Figure 1 is a front elevation of one form of my novel construction of a multiplex fuse

cartridge; Fig. 2 is a side elevation of the same; Fig. 3 is a longitudinal section of the same, taken on line 3—3 in said Fig. 1; Fig. 4 is a longitudinal section of the same, 60 taken on line 4—4 in said Fig. 2; and Fig. 5 is a transverse section of the same, taken on line 5—5 in said Fig. 3.

Fig. 6 is a fragmentary front elevation of a modified form of my novel multiplex fuse 65 cartridge; and Fig. 7 is a longitudinal section of the same, taken on line 7—7 in said Fig. 6.

Fig. 8 is a longitudinal section of another modified form of my novel multiplex fuse 70 cartridge; and Fig. 9 is a transverse section of the same, taken on line 9—9 in said Fig. 8.

Fig. 10 is a longitudinal section of still another modified form of my novel multiplex fuse cartridge.

75

Similar characters of reference are employed in all of the hereinabove described views, to indicate corresponding parts.

Referring now to said drawings, the reference-character 1 indicates a tubular casing 80 constructed of some suitable insulating material. The ends of said casing 1 are respectively closed by metallic caps 2 and 3, which telescope over the said ends of said casing, the same being immovably fixed in 85 said relation by means of fastening screws 4, or by any other suitable form of fastening means.

Secured within the inclosed chamber of the casing 1, intermediate the ends of the 90 same, is a transverse metallic disk or partition member 5, which divides the interior of said casing into a fuse compartment 6 extending between one side of said partition member and the end cap 2, and a fuse compartment 7 extending between the other side of said partition member and the opposite end cap 3.

Extending longitudinally and centrally through the fuse compartment 6 is a fuse 100 element or wire 8, having its outer end suitably secured in electrical and mechanical engagement with the cap 2 and its inner end suitably secured in electrical and mechanical engagement with the metallic disk or partition member 5. In like manner, a second fuse element or wire 9 is arranged to extend longitudinally and centrally through the fuse compartment 7, having its outer end suitably secured in electrical and mechanical 105 engagement with the cap 3 while its inner end is suitably secured in electrical and 110 mechanical engagement with the metallic disk or partition member 5.

mechanical engagement with the metallic disk or partition member 5. It will be noted that the metallic disk or partition member 5 serves as a common electrical connection for each fuse element or wire, whereby the same are electrically connected in series between the respective caps 2 and 3.

Preferably one fuse compartment is of a slightly reduced diameter as compared with the other, so that an annular shoulder 10 may be provided against which said metallic disk or partition member is seated, so that the same is maintained against turning out of its normal transverse disposition within the casing.

In the form of my invention illustrated in Figs. 1 to 5 inclusive of the drawings, I provide the metallic disk or partition member 5 with oppositely and outwardly struck loop or bowed portions 11, which mutually serve to furnish a bearing in which is journaled a transverse rotatable contact pin or spindle 12, the ends of which project outwardly through the walls of said casing. One end 25 of said contact pin or spindle 12 is provided with an exterior head 13 serving to prevent axial displacement of the same in one direction, and secured to the opposite exterior end of said pin or spindle is an exterior contact 30 arm 14, fastened by riveting over a reduced extension 15 of said pin or spindle which projects through the inner end of said contact arm. Said contact arm 14 is of sufficient length, that, when the same is positioned to extend longitudinally along said 35 casing 1, the free end of the same will engage one or the other of said caps 2 and 3. Preferably the free end of said contact arm 14 is provided with a concavo-convexly 40 shaped portion 16 which conforms to the circumferences or cylindrical surfaces of the caps 2 and 3, so that when engaged with either cap the inherent spring or resiliency of the arm will cause said portion 16 to 45 firmly engage the cap surface, and be thereby retained against accidental displacement. From the above it will be clear that in the 50 form described, I provide a very practical fuse cartridge of the duplex type. In the use of the novel fuse cartridge of the duplex type, thus constructed, when the same is placed in service in an electrical circuit, the contact arm 14 is turned so that its end portion 16 is in contact with said cap 3, 55 with the consequence that the fuse element or wire 9 is short circuited, or in other words cut out of service. When thus arranged the path which the electric current takes through the fuse cartridge is as follows:—

60 Assuming the current to enter at the cap 2, the same flows through the operative fuse element or wire 8 to the metallic disk or partition member 5, flowing thence through the pin or spindle 12 and contact arm 14 to 65 the cap 3 from whence it leaves the fuse

cartridge. It will be apparent that an overload of current in the circuit in passing through the fuse element or wire 8 will cause the latter to "blow" thus interrupting the circuit until a new fuse is inserted. Assuming that the first fuse element or wire 8 has "blown" all that it is necessary to do in order to place the second fuse element or wire 9 in service, and thereby operatively close the circuit again, is to turn the contact 70 arm 14 around, thereby removing the same from engagement with the cap 3 and causing the same to engage the cap 2 (in the manner indicated by the dotted lines in Fig. 1 of the drawings). The contact arm 14 now becomes a bridging conductor across the gap between the cap 2 and metallic disk or partition member 5 which has occurred by reason of the "blowing" of the fuse element or wire 8, so that the current entering the said 75 cap 2 is conducted by the contact arm 14 and pin or spindle 12 to the disk or partition member 5, whence it flows through the second fuse element or wire 9 to the cap 3, thus placing said second fuse element or wire 80 in service. In order to indicate to the user a proper initial arrangement of the contact arm 14 relative to the caps 2 and 3, and as a guide in operating the contact arm when changing the same from one operative position to the other, the caps may be respectively given differentiating identifying 85 marks such as the mark "1" on the cap 3 and the mark "2" on the cap 2, as shown in Fig. 1 of the drawings.

From the above description it will be readily understood that my novel construction of fuse cartridge provides a double service capacity, and may be very easily manipulated to place the same in service a second time, so that for the slight additional material and labor cost of the disk 5 and contact arm 14 with the interconnecting spindle or pin 12, two independent fuses are provided in the one device for but little 105 more than the cost of an ordinary single fuse cartridge, and for considerably less than the cost of two single fuse cartridges, to say nothing of the added convenience of having a second fuse immediately ready for 110 insertion in circuit. Another advantage of my novel fuse cartridge is its safety, since should the contact arm be accidentally displaced from engagement with the caps, no 115 risks would be incurred because, in that event, both fuse elements or wires 8 and 9 would be simultaneously in circuit, as the same are connected in series, consequently the circuit would be protected under all 120 circumstances against the dangers incident to 125 overloads.

Referring now to Figs. 6 and 7 of the drawings, I have shown a slightly modified construction of my novel multiplex fuse cartridge, which is also illustrated in the du- 130

plex form and which operates in the same manner and with the same effects as already above described. In this construction the metallic disk or partition member 5' is made 5 somewhat thicker, and is provided with a diametrically extending bore 17. Extending through the walls of the casing 1 and journaled in the bore 17 is a pin or spindle 18, headed, as at 19, at its lower exterior end 10 and provided at its upper exterior end with an integrally formed longitudinally extending contact arm 20. The respective caps are provided with a pair of laterally spaced tits or bosses 21, or other equivalent holding 15 means, which serve to engage or straddle the free end of said contact arm 20, when the same is operatively engaged with a cap, to hold the same against accidental displacement.

20 Referring now to Figs. 8 and 9 of the drawings, I have another modified form of my multiplex fuse cartridge of the duplex type which embodies, however, the general principles of my invention. In this construction the metallic disk or partition member 5'' is provided with a suitably located internally screw-threaded opening 22, and in place of the pivoted contact arms 14 or 20 of the previously described constructions, 25 I provide a short circuiting element in the form of a removable screw 23 adapted to be passed through an opening 24 provided in the caps 2' and 3' so that its threaded end may screw into said threaded opening 22 of the metallic disk or partition member 5''. It will be apparent that by passing the screw 23 through the opening of the cap 3' and engaging the same with metallic disk or partition member 5'', the fuse wire or element 9 30 will be short circuited, but when the fuse wire or element 8 is blown, by removing the screw 23 and passing the same through the cap 2' into engagement with the metallic disk or partition member 5'', the same serves 35 to bridge the current across the gap between the cap 2' and disk or partition member 5'' caused by the "blown" fuse 8, and at the same time permits the current to flow operatively through the fuse wire or element 9, 40 thus putting the latter in service. In order to provide a clear or open passage for the screw between the caps 2' and 3' and the disk or partition member 5'' when the fuse chambers are filled with the usual filler 45 powder, I provide sleeves 25 of insulating material extending between each cap and said disk or partition member, the same being secured and held in position by engaging their ends over annular bosses or shoulders 50 26 projecting from the respective caps and from each side of the disk or partition member concentric to their respective openings 24 and 22.

It will be understood that each fuse chamber 6 and 7 may be filled with a filler powder

such as is commonly used in fuse cartridges, and which is adapted to absorb the vapors generated by the burning of the fuse element or wires 8 and 9, although in order not to interfere with the clear illustration of the 70 construction of my invention, graphic illustration of such filler powder has been omitted from the drawings.

The principles of my invention as applied in the structures illustrative thereof and 75 above described, may also be applied to multiplex fuse cartridges of the triplex, quadruplex, etc., types, in other words to fuse cartridges provided with three or more fuse elements. This is illustrated by the structure shown in Fig. 10 of the accompanying 80 drawings. In this structure I arrange a plurality of metallic disks or partition members 5''' within the casing 1', which serve to connect in series, between the caps 2 and 3, the 85 plurality of fuse elements *a*, *b*, *c* and *d*. Arranged in swiveling and electrical connection with the respective partition members 5''' are the contact arms *x*, *y* and *z*. As shown in said Fig. 10, the contact arms are relatively arranged so as to short circuit the 90 fuse elements, *a*, *b* and *c* while leaving the fuse element *d* in service; the contact arm *x* being engaged with the cap 2, while the contact arm *y* engages the arm *x* and the 95 contact arm *z* engages the arm *y*. When the fuse *d* "blows" the fuse *c* may be put in service by turning the arm *z* away from the arm *y* into engagement with the cap 3. When the fuse *c* "blows" the fuse *b* may be put in 100 service by turning the arm *y* into engagement with the arm *z* while contacting with the cap 3; and when the fuse *b* "blows", the fuse *a* may be put in service by turning the arm *x* away from cap 2 and into engagement 105 with arm *y*. It will thus be apparent that each fuse may be successively put into use, and that the multiplex fuse cartridge thus constructed and operated involves the same principles of operation no matter what the 110 number of fuse elements may be.

I am aware that some changes may be made in the general arrangements and combinations of the various devices and parts of my present invention, without departing 115 from the scope of said invention as set forth in the foregoing specification and as defined in the appended claims. Hence, I do not limit my present invention to the exact arrangements and combinations of the various 120 devices and parts as described in the said specification, nor do I confine myself to the exact details of the construction of the said parts as illustrated in the accompanying drawings.

I claim:—

1. A multiplex fuse cartridge comprising a casing having external terminal caps on its opposite ends, a plurality of fuse elements connected in series between said ter- 130

- 10 minal caps, and means for connecting in circuit between said caps but one fuse element at a time.
- 15 2. A multiplex fuse cartridge comprising a casing having external terminal caps on its opposite ends, a fuse element connected with each terminal cap, intermediate means between said fuse elements for electrically connecting the same in series, and means 20 interchangeably and electrically connected with said intermediate means and one or the other of said caps for short circuiting one of said fuse elements while the other is in service.
- 25 3. A multiplex fuse cartridge comprising a casing having external terminal caps on its opposite ends, an internal metallic partition member intermediate the ends of said casing, a fuse element interconnected between each cap and said metallic partition member, and a conducting means for interchangeable electrical connection between said metallic partition member and one or the other of said caps for the purposes described.
- 30 4. A multiplex fuse cartridge comprising a casing having external terminal caps on its opposite ends, an internal metallic partition member intermediate the ends of said casing, a fuse element interconnected between each cap and said metallic partition member, and a pivotal conducting means electrically connected with said metallic partition member and movable into electrical engagement with either one or the other of said terminal caps.
- 35 5. A multiplex fuse cartridge comprising a casing having external terminal caps on its opposite ends, a fuse element interconnected between each cap and said metallic partition member, an internal metallic partition member intermediate the ends of said casing, and an external contact arm secured to an outer end of said spindle, the free end of said contact arm being interchangeably movable into electrical engagement with either one or the other of said terminal caps.
- 40 6. A duplex fuse cartridge comprising a casing having external terminal caps on its opposite ends, an internal metallic partition member intermediate the ends of said casing, a fuse element interconnected between each cap and said metallic partition member, a transverse spindle journaled to extend through the walls of said casing and in electrical contact with said metallic partition member, and an external contact arm secured to an outer end of said spindle, the free end of said contact arm being interchangeably movable into electrical engagement with either one or the other of said terminal caps.
- 45 7. A duplex fuse cartridge comprising a casing having external terminal caps on its opposite ends, an internal metallic partition member intermediate the ends of said casing, a fuse element interconnected between each cap and said metallic partition member, a transverse spindle journaled to extend through the walls of said casing and in electrical contact with said metallic partition member, an external contact arm secured to an outer end of said spindle, the free end of said contact arm being interchangeably movable into electrical engagement with either one or the other of said terminal caps.
- 50 8. A duplex fuse cartridge comprising a casing having external terminal caps on its opposite ends, an internal metallic partition member intermediate the ends of said casing, a fuse element interconnected between each cap and said metallic partition member, a transverse spindle journaled to extend through the walls of said casing and in electrical contact with said metallic partition member, an external contact arm secured to an outer end of said spindle, the free end of said contact arm being interchangeably movable into electrical engagement with either one or the other of said terminal caps.
- 55 9. A duplex fuse cartridge comprising a casing having external terminal caps on its opposite ends, an internal metallic partition member intermediate the ends of said casing, a fuse element interconnected between each cap and said metallic partition member, a transverse spindle journaled to extend through the walls of said casing and in electrical contact with said metallic partition member, an external contact arm secured to an outer end of said spindle, the free end of said contact arm being interchangeably movable into electrical engagement with either one or the other of said terminal caps.
- 60 10. A duplex fuse cartridge comprising a casing having external terminal caps on its opposite ends, an internal metallic partition member intermediate the ends of said casing, a fuse element interconnected between each cap and said metallic partition member, a transverse spindle journaled to extend through the walls of said casing and in electrical contact with said metallic partition member, an external contact arm secured to an outer end of said spindle, the free end of said contact arm being interchangeably movable into electrical engagement with either one or the other of said terminal caps.
- 65 11. A duplex fuse cartridge comprising a casing having external terminal caps on its opposite ends, an internal metallic partition member intermediate the ends of said casing, a fuse element interconnected between each cap and said metallic partition member, a transverse spindle journaled to extend through the walls of said casing and in electrical contact with said metallic partition member, an external contact arm secured to an outer end of said spindle, the free end of said contact arm being interchangeably movable into electrical engagement with either one or the other of said terminal caps.
- 70 In testimony that I claim the invention set forth above I have hereunto set my hand this 4th day of May, 1920.
